UNITED STATES PATENT OFFICE.

MARTIN KALLMANN, OF CHARLOTTENBURG, GERMANY; PAULA KALLMANN, OF BERLIN, GERMANY, ADMINISTRATRIX OF SAID MARTIN KALLMANN, DECEASED.

ARMORED, FLAT, ELECTRICAL CONDUCTOR.

1,162,614.

Specification of Letters Patent.

Patented Nov. 30, 1915.

Application filed December 14, 1911. Serial No. 665,689.

To all whom it may concern:

Be it known that I, MARTIN KALLMANN, a subject of the German Emperor, and residing at Charlottenburg, near Berlin, Germany,

5 have invented certain new and useful Improvements in Armored, Flat, Electrical Conductors, of which the following is a specification.

This invention relates to armored flat electrical conductors.

10 The invention contemplates the use of a resilient metallic tape and an insulated conductor applied thereto in any suitable manner. Means for spacing the tape from the wall or the like are applied on the opposite side to that on which the conductor is located. If the conductor be not independently insulated it may be embedded in a coating of insulating material applied to the 15 metallic tape. In connecting the conductor and the tape, wire clips extending around both elements may be employed.

In the drawings: Figure 1 is a view of the device in transverse section; Fig. 2 is a 20 plan view looking from the lower side of Fig. 1.

It will be observed that I have illustrated a steel tape 10 which may be provided with small perforations 11 near its edges for the 25 accommodation of the fastening devices referred to below.

The copper conductor is indicated by 12, this conductor being embedded in suitable insulating adhesive substance 15, and also 30 being insulated on the side opposite the steel tape with a paper strip 16, the latter being embedded in the adhesive material if desired.

The tape may be spaced from the wall to

which it is secured by insulating spacing 40 members 17, and wire clips 18 extend transversely for holding the parts securely together.

While I have described specific means for carrying my invention into effect, I do not desire to be limited to all of the details of construction mentioned, but may make such changes or alterations as fall within the scope of the appended claims.

What I claim is:

1. A device of the class described comprising a resilient metallic strip having applied thereto a coating of adhesive material constituting a non-conductor, and a conductor embedded in the coating and insulated thereby from the strip. 50

2. A device of the class described comprising a flexible strip having applied thereto a coating of adhesive material, and a conductor embedded in the coating and insulated thereby from the strip, spacing means on the opposite side of the conductor, and a securing device extending about said elements and transversely of the strip. 60

3. A device of the class described comprising a resilient metallic strip having applied thereto a coating of insulating material, a conductor embedded in the coating, and means bent about the conductor at intervals for mechanically securing the latter to the strip. 65

In testimony whereof, I affix my signature in the presence of two witnesses.

MARTIN KALLMANN.
